(57) **CLAIM**

We claim the ornamental design for a molding-system platen, as shown and described.

DESCRIPTION

FIG. 1 is a perspective view of the back side of an embodiment of the molding-system platen;

FIG. 2 is a perspective view of the front side of the molding-system platen of FIG. 1;

FIG. 3 is a view of the right side of the molding-system platen of FIG. 1;

FIG. 4 is a view of the back side of the molding-system platen of FIG. 1;

FIG. 5 is a view of the left side of the molding-system platen of FIG. 1;

FIG. 6 is a view of the front side of the molding-system platen of FIG. 1;

FIG. 7 is a view of the top side of molding-system platen of FIG. 1; and,

FIG. 8 is a view of the bottom side of molding-system platen of FIG. 1.
